UNITED STATES PATENT OFFICE.

CYRIL PERCY RYAN, OF EAST MOLESEY, ENGLAND, ASSIGNOR TO VICKERS LIMITED, OF WESTMINSTER, ENGLAND, A BRITISH COMPANY.

RADIO SIGNALING AND CONTROL.

Application filed February 27, 1924. Serial No. 695,397.

To all whom it may concern:

Be it known that I, CYRIL PERCY RYAN, a subject of the King of Great Britain, residing at Shotley House, East Molesey, in the county of Surrey, England, have invented certain new and useful Improvements in Radio Signaling and Control, of which the following is a specification.

This invention relates to an improved 10 radio system whereby signals may be transmitted to a receiving station and employed to operate a recorder or any apparatus it is desired to control, the chief object of the invention being to provide a system which 15 will effectively prevent any danger of an outside station ascertaining the nature of the signals and interfering with the operation of the receiver.

In the improved system radio controlling 20 impulses are sent from the transmitting station at regularly timed intervals at a predetermined acoustic frequency or frequencies to which the receiving apparatus is tuned, together with impulses of other acoustic 25 frequencies succeeding or superposed upon the operating impulses or signals to produce an apparently incoherent or confused succession of impulses and the radio receiver operates an acoustic transmitter which in its 30 turn operates an acoustic receiver tuned to respond only to the signaling frequency and controlling, through suitable relaying means, an electric circuit which acts upon an oscillatory inertia member whose natural period 35 of swing is that of the timed impulses and which is adapted to build up its oscillations of successive impulses until their amplitude reaches a predetermined amount, whereupon the said member operates an electrical actuating circuit to produce any pre-arranged 40 effect.

The accompanying drawings illustrate 45 diagrammatically in Figure 1 the complete system, the transmitter being shown at the left hand side and the receiving and controlling apparatus at the right, while Figure 2 illustrates a slight modification of the receiving apparatus. The radio apparatus illustrated in the diagrams is given merely 50 by way of example as the arrangement of valves and circuits is of standard type and may embody any appropriate standard practice.

A is the oscillating inertia member in the 55 form of a wheel or disc pivoted at α in a

support B and controlled by the coiled spring C which determines the natural oscillation period of the wheel. The spring is attached at one end to the pivot pin α and at the other to a stud β on the support B, 60 the spring being adjusted to any period desired. D, D' are controlling electromagnets, two being shown in the arrangement illustrated, the cores d of which approach the periphery of the wheel A. The latter is 65 provided with a pair of wedge shaped soft iron pole pieces a' at opposite sides of the wheel and adjacent to the electromagnets. The wedge form of the pole pieces a' is intended to give a smoother and more regular action to the wheel when controlled by the electromagnets D, D' so that the wheel oscillations steadily build up as successive 70 timed impulses are given.

The wheel is used to control any desired 75 operation when a given amplitude has been attained, by, for example, closing an electrical circuit E through a contact arm a'' on the wheel spindle or pivot pin α and a stationary contact spring e .

In the general arrangement of apparatus shown in Figure 1 a tuned antenna circuit F is employed with a valve G in an ordinary radio receiving circuit and a telephone receiver or sound emitter H of loud speaker type emits the controlling signals as sound vibrations. The transmitting apparatus diagrammatically indicated at the left hand side of Figure 1 comprises a radio transmitter of ordinary type adapted to send impulses of audio frequency on a carrier wave of high frequency. In the diagram J is the transmitting aerial with tuning inductance j and variable condenser j' . K is the oscillating valve having its grid coupled to 90 the tuned inductance j through the coil k . L is a modulating valve operated through the low frequency transformer M, the primary of which is in the circuit n of the microphone N. O is the power source, indicated as a dynamo, and a low frequency choking coil P is inserted in the circuit between the modulating valve and the current source and a high frequency choking coil P' inserted between the two valves. To 105 transmit the controlling signals at the required rate and having the desired acoustic frequency or frequencies (two being employed in the particular arrangement illustrated) a sound record disc Q is indicated 110

on which rests the usual gramophone needle R, the lever r of which operates the microphone N. The sound record disc is cut with a record giving, when the disc is rotated at the proper speed, a succession of signals at the required acoustic frequency or frequencies to operate the receiving circuit and timed to the natural low frequency period of the oscillating wheel A. Superposed upon these operating signals are other inoperative or confusing signals impressed upon the record in order and simultaneous with or interposed between the operating signals so that a listener in would 10 find it impossible to detect the controlling system, while the superposed or confusing signals have no effect upon the timed receiving system. In the dual control, illustrated by way of example, with two controlling 15 electromagnets D, D', two frequencies would be employed of say, 1,000 and 1,500 per second, the impulses of the two frequencies being alternated.

To excite the two electro-magnets D, D' independently of one another by means of the two transmitted frequencies two tuned acoustic receivers S, S' are placed adjacent to the sound emitter H, these tuned receivers responding to the two different notes, 20 say 1,000 and 1,500 vibrations per second respectively. The acoustic tuning is effected in any known manner as, for example, by altering the effective length of the receivers S, S' by the telescopic tube arrangement 25 shown. Each receiver S, S' carries an electrical transmitter s, which may be a microphone in the circuit T which includes the battery t, operating the corresponding local telephone receiver U or U' which serves as 30 a relay for the local circuit V or V' with batteries v, v' controlled through the chattering contacts W, W' the light almost balanced contact arm resting on a reed u belonging to the receiver U or U'. When one 35 of the tuned acoustic receivers S or S' receives an impulse of the note to which it is tuned the telephone receiver U or U' is affected and the vibration of the oscillating member or reed u causes the contact arm W 40 or W' to jump and by the intermittent breaking of the circuit U or U' to alter the current in the electromagnet D or D'. In the arrangement shown the magnets D, D' are normally excited by the small current 45 passing through the local circuit V or V' so that they exercise a normal attraction upon the wedge-shaped pole pieces a' of the wheel A, while any reduction in the magnetic flux due to the intermittent breaking of the 50 exciting circuit allows the spring C to turn the wheel. By properly timing the operation of the impulses the swing of the wheel increases and the amplitude is built up until the circuit E is closed through the contact 55 a² and e.

The chattering contact relay shown in Figure 1 is, of course, given merely as an example and another method of operating the wheel is indicated in the diagram, Figure 2, where the acoustic receivers S, S' 60 operate the microphone circuits T², T³ each having the primary t' of a transformer, the secondary v' of which is in the electromagnet circuit V², V³, which includes a rectifier v². The receiver impulses acting through 65 the tuned acoustic receivers cause the corresponding electromagnets to be excited intermittently through the rectified current in the local electromagnet circuits, the action of the wheel being the reverse of that previously described, as the electromagnets are excited at each impulse instead of having their normally acting exciting circuits interrupted.

What I claim and desire to secure by Letters Patent of the United States is:—

1. In a radio signaling control system, means for emitting a regularly timed succession of operative radio signals each of predetermined acoustic frequency, together with signaling impulses of other acoustic frequencies, tuned receiving apparatus adapted to respond only to the said operative radio signals and oscillatory mechanism operated through the said receiving apparatus and having an oscillation period corresponding to the said timed succession of impulses.

2. In a radio signaling control system, means for automatically operating radio transmitting apparatus to send a regularly timed succession of operative radio signals each of predetermined acoustic frequency, together with signaling impulses of other acoustic frequencies, tuned receiving apparatus adapted to respond only to the said operative radio signals and oscillatory mechanism operated through the said receiving apparatus and having an oscillation period corresponding to the said timed succession of impulses.

3. In a radio signaling system, a single sound recording member having impressed upon it a succession of signals at a predetermined acoustic frequency, together with signals of other acoustic frequencies adapted to confuse the first mentioned signals, a radio transmitting apparatus operated under the control of the signaling sound record and tuned receiving apparatus to respond only to the first mentioned signals.

4. In a radio signaling system a radio transmitter adapted to send impulses of acoustic frequency and a single sound recording apparatus adapted to control the said radio transmitter, which sound recording apparatus has impressed upon it a succession of signals of other predetermined acoustic frequencies adapted to mask the aforesaid succession of signals.

5. In a system or radio signaling control employing acoustic frequencies, a radio receiving apparatus, a sound emitter operated by the radio receiving apparatus, an acoustic receiver tuned to respond only to a predetermined signaling frequency, an electrical circuit controlled by the said acoustic receiver and an oscillatory inertia member having a natural low period of swing under the control of the said electrical circuit and adapted to build up oscillations by successive impulses timed to the natural period of swing.

6. In a system of radio signaling control as claimed in claim 5, an electrical circuit controlled by the oscillatory inertia member and means for operating the said circuit by the aforesaid oscillatory inertia member when the amplitude of the swing of the latter reaches a predetermined amount.

7. In a system of radio signaling control, a radio telephone transmitter, means for transmitting a regularly timed succession of signaling impulses at predetermined acoustic frequency, a radio receiver, an emitter adapted to be operated by the said radio receiver, an acoustic receiver tuned to respond only to the signaling acoustic frequency, an electrical circuit operated by said acoustic receiver and an oscillatory inertia member under the control of the said circuit, the natural period of swing of the said member corresponding to the timing of the controlling signals, whereby the inertia member may build up its oscillations by the successive timed impulses.

8. In a system of radio signaling control employing acoustic frequencies, a radio receiving apparatus, a sound emitter operated by the radio receiving apparatus, an acoustic receiver tuned to respond only to a predetermined signaling frequency, an electrical circuit controlled by the said acoustic receiver, a wheel mounted to oscillate under spring control with a natural low period of swing, and means whereby the said wheel may be given impulses by the said electrical circuit, which impulses cause the

wheel to oscillate and to build up its oscillations.

9. In a system as claimed in claim 8, an electrical circuit under the control of the oscillating wheel and a control device in the said circuit operated by the wheel when the oscillations of the latter attain a predetermined amplitude.

10. In a radio signaling system, a radio transmitter adapted to send signals of acoustic frequency and means for automatically producing a timed succession of signaling impulses at the transmitter having a predetermined acoustic frequency, together with signaling impulses of other frequencies adapted to mask the aforesaid succession of signaling impulses, a radio receiving circuit, a second emitting device under the control of the said receiving circuit, a sound receiver tuned to the acoustic frequency of the first mentioned signaling impulses, an electrical circuit under the control of the said sound receiver an oscillatory inertia member and means whereby the said sound controlled electrical circuit impresses successive impulses on the said inertia member.

11. In a radio signaling system, a radio transmitter adapted to send signals of acoustic frequency, means by which a timed succession of operative signals having a plurality of predetermined frequencies are transmitted, together with signaling impulses of other frequencies adapted to mask the aforesaid succession of operative signals, radio receiving apparatus, a sound emitting device under the control of the receiver, a plurality of sound receivers tuned to the plurality of frequencies of the aforesaid operative signals and corresponding electrical circuits operated by the said sound receivers, whereby only those frequencies employed for the operative signals are effective for their respective electrical circuits and oscillatory inertia member adapted to be actuated by the said electrical circuits as operated by the timed successive signals.

CYRIL PERCY RYAN.
